UNITED STATES PATENT OFFICE.

EVERETT H. BICKLEY, OF UPPER DARBY, PENNSYLVANIA.

DESIGN FOR A FAUCET.

Application filed October 3, 1922. Serial No. 3,875. Term of patent 3½ years.

To all whom it may concern:

Be it known that I, EVERETT H. BICKLEY, a citizen of the United States, and a resident of Upper Darby, county of Delaware, State of Pennsylvania, have invented a new, original, and ornamental Design for Faucets, of which the following is a specification, reference being had to the accompanying drawing, forming a part thereof.

Fig. 1 represents a plan of a faucet embodying the design of the present invention; Fig. 2 represents a front elevation of the same; and Fig. 3 represents a side elevation of the same.

I claim:

The ornamental design for a faucet substantially as shown.

EVERETT H. BICKLEY.
